UNITED STATES PATENT OFFICE.

JOHN W. DOUGLAS, OF SHELBOURNE, ONTARIO, CANADA.

DESIGN FOR A WEEDING-HOE.

SPECIFICATION forming part of Design No. 19,562, dated January 7, 1890.

Application filed August 12, 1889. Serial No. 320,530. Term of patent 7 years.

To all whom it may concern:

Be it known that I, JOHN WILLIAM DOUGLAS, barrister at law, a subject of the Queen of Great Britain, residing at the village of 5 Shelburne, in the county of Dufferin, in the Province of Ontario, Canada, have invented and produced a new and original Design for Weeding-Hoes, of which the following is a specification, reference being had to the accompanying drawing, forming part thereof.

In the drawing, which shows a perspective of a hoe constructed according to my design, A represents a flat steel plate having a shank B, diamond-shaped in cross-section, and handle C. The back edge *a* of the plate A is

angled inwardly, so as to be approximately V-shaped.

What I claim as my design is—

The design for a hoe, consisting of a flat plate A, provided with a slanting shank diamond-shaped in cross-section rising from near its longitudinal center, and having its rear edge or side angled inwardly in lines parallel to the front edge, being approximately V-shaped, as described and shown.

Shelburne, July 17, 1889.

JNO. W. DOUGLAS.

In presence of—

J. C. LANSING,
H. J. RALSTON.
